CLAIM

The ornamental design for a towel, as shown and described.

DESCRIPTION

FIG. 1 is a perspective view of the towel, showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an enlarged view of an area labeled 8 in FIG. 1.
